US00D783028S

(12) **United States Design Patent** (10) **Patent No.:** **US D783,028 S**
Lee et al. (45) **Date of Patent:** **** Apr. 4, 2017**

(54) **DISPLAY SCREEN OF A NAVIGATION DEVICE FOR A VEHICLE WITH A GRAPHICAL USER INTERFACE**

(71) Applicant: **LG ELECTRONICS INC.**, Seoul (KR)

(72) Inventors: **Kunsik Lee**, Seoul (KR); **Junsic Park**, Seoul (KR); **Swoon Yoon**, Seoul (KR); **Kyoungjune Shin**, Seoul (KR)

(73) Assignee: **LG ELECTRONICS INC.**, Seoul (KR)

(**) Term: **15 Years**

(21) Appl. No.: **29/542,861**

(22) Filed: **Oct. 19, 2015**

(30) **Foreign Application Priority Data**

Apr. 27, 2015 (KR) 30-2015-0021583

(51) LOC (10) Cl. **14-04**

(52) U.S. Cl.

USPC **D14/485**

(57) **CLAIM**

The ornamental design for a display screen of a navigation device for a vehicle with a graphical user interface, as shown and described.

DESCRIPTION

The sole FIGURE is a front view of a display screen of a navigation device for a vehicle with a graphical user interface showing our new design.

The broken lines showing a display screen illustrate portions of the article and form no part of the claimed design.

1 Claim, 1 Drawing Sheet
